UNITED STATES PATENT OFFICE.

AUGUST WEINGAERTNER, OF CHICAGO, ILLINOIS, ASSIGNOR TO
NATIONAL BISCUIT COMPANY, OF CHICAGO, ILLINOIS, A COR-
PORATION OF NEW JERSEY.

GREASE AND MOISTURE PROOF PAPER.

No. 828,004.

Specification of Letters Patent.

Patented Aug. 7, 1906.

Application filed May 22, 1905. Serial No. 261,564.

To all whom it may concern:

Be it known that I, AUGUST WEINGAERTNER, a citizen of the United States, residing at Chicago, in the county of Cook and State of Illinois, have invented certain new and useful Improvements in Grease and Moisture Proof Papers, of which the following is a specification.

This invention relates to improvements in grease and moisture proof papers; and it has for its salient objects to provide a paper which while having the characteristics referred to is at the same time devoid of such chemicals and other ingredients as would tend to contaminate food products when wrapped therein; to provide a paper of the character referred to so treated that it will keep indefinitely without deterioration or chemical change; to provide a paper which may be very inexpensively made and which is not sensitive to weather conditions, such as heat, moisture, and the like; to provide a paper which is substantially air-proof, and in general to provide an improved article of the character referred to.

My improved paper is made by treating any ordinary suitable paper-stock—*i. e.*, finished paper—by applying thereto an impregnating solution and a subsequent moisture-proof coating.

In carrying out my invention in a preferred manner I make a solution of casein by dissolving about two hundred parts of ordinary commercial casein in a sufficient quantity of alkaline water to fully liquefy the casein. To facilitate the dissolving of the casein, I add to the water in which it is to be dissolved about fifty parts, by weight, of strong aqua-ammonia (aqua-fortior) and preferably also warm the liquid. After the casein has been dissolved I add about fifty parts, by weight, of a very dilute commercial aqueous solution of sulfurous acid and about one part, by weight, of a fluorid salt. By preference I use bifluorid of ammonia; but I may substitute therefor bifluorid of sodium or of potassium or free hydrofluoric acid. After these ingredients have been thoroughly mixed I dilute the mixture by the addition of about seventeen hundred parts of water, and the mixture is then ready for use as a bath, through which the paper may be passed. Of course if there are impurities in the chemicals the

mixture may be strained or filtered before use. Through the bath thus prepared I 55 pass any suitable absorbent paper, subjecting the paper to the action of the bath long enough to permit it to become substantially saturated therewith. Of course the mixture may be applied to the paper otherwise than 60 by passing it through the bath. After the paper has been treated and dried I then proceed to render it moisture-proof by coating it, usually on one side only, with a suitable water-repudiating substance, such as paraffin-wax or the like. This coating may be accomplished in any usual and well understood way.

While I prefer to use the above proportions of ingredients, it will be understood that the 70 proportions may be varied to suit varying conditions, grades, and characters of paper.

A paper made in accordance with the foregoing description possesses the characteristics stated in the objects of the invention and forms a valuable article for wrapping food products and other uses where it is desired to have a weatherproof package and a wrapping which is impervious to grease and oils. The action of the aqueous solution of sulfurous acid on the casein is analogous to the action of formaldehyde upon the same substance; but the aqueous solution of sulfurous acid is not only much less expensive, but it is also in the combination employed by me perfectly innocuous. An important function of the fluorid salts or free hydrofluoric acid in the compound is its preservative action upon the casein.

I claim as my invention—

1. As a new article of manufacture, a pa-

per impregnated with a compound resulting

from the union of casein, an aqueous solution

of sulfurous acid, and a preservative.

2. As a new article of manufacture, a pa-

per impregnated with a compound resulting

from the union of casein, an aqueous solution

of sulfurous acid, and a fluorid salt or free

hydrofluoric acid.

3. As a new article of manufacture, a pa-

per impregnated with a compound resulting

from the union of an aqueous solution of sul-

furous acid, casein, ammonia, and a fluorid

salt or free hydrofluoric acid.

4. As a new article of manufacture, a pa-

per impregnated with a compound resulting

from the union of casein, an alkaline solvent of casein, an aqueous solution of sulfurous acid, and a preservative.

5. As a new article of manufacture, a paper impregnated with a compound resulting from the union of casein, an aqueous solution of sulfurous acid, and a preservative, and coated with a moisture-repelling film.

6. As a new article of manufacture, a pa-

per impregnated with a componnd resulting from the union of casein, an aqueous solution of sulfurous acid, and a fluorid salt, and coated upon one side with a film of paraffin. 10

AUGUST WEINGAERTNER.
